235,800

OCULAR ASSEMBLY FOR A RIFLESCOPE

Gerrit A. Van Exel, Fullerton, Calif., assignor to Bausch & Lomb Incorporated, Rochester, N.Y.

Filed Apr. 25, 1973, Ser. No. 354,212

Term of patent 14 years

Int. Cl. D16—06

U.S. CL. D57—1 E

Fig. 1

Fig. 2

Fig. 3

Fig. 4

Fig. 5

FIG. 1 is a side elevation of an ocular assembly for a riflescope;

FIG. 2 is an end view of the housing taken from the left end of FIG. 1 and showing the housing as seen by a rifleman when the housing is mounted on a riflescope body;

FIG. 3 is an end view of the housing taken from the right end of FIG. 1 and showing the end of the housing which is adapted to mate with a riflescope barrel;

FIG. 4 is a top view of the housing; and

FIG. 5 is a bottom view of the housing.

I claim:

The ornamental design for an ocular assembly for a riflescope, substantially as shown and described.
